AUTOMATIC COUPLING DEVICE

Filed Nov. 24, 1928

UNITED STATES PATENT OFFICE

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA

AUTOMATIC COUPLING DEVICE

Application filed November 24, 1928. Serial No. 321,548.

This invention relates to automatic train pipe couplings, and more particularly to the type known as the tight or rigid lock coupling.

5 An object of the invention is to provide a train pipe coupling of the above mentioned type wherein the brake pipe will be automatically closed when the cars are uncoupled, will be automatically opened when the cars 10 are coupled together, and will remain open in case the cars are unintentionally uncoupled.

Another object of the invention is to provide an improved train pipe coupling of the 15 character mentioned which is relatively simple in construction, and reliable and exact in function under all conditions of service.

The invention also comprises certain new 20 and useful improvements in the construction, arrangement and combination of the several parts of which it is composed, as will be hereinafter more fully described and claimed.

In the accompanying drawings: Figure 1 25 is a plan, partly in section, of a train pipe coupling embodying my invention, showing the same in uncoupled position; Fig. 2 is a transverse section taken along the line 2—2 of Fig. 1; Fig. 3 is a view similar to Fig. 2 30 showing the parts in coupled position; Fig. 4 is a longitudinal section taken along the line 4—4 of Fig. 1 showing the parts in coupled position; and Fig. 5 is a side view of a portion of the latch operating member.

35 Train pipe couplings of the type known as the tight or rigid lock coupling, are shown for example, in the Westinghouse Patent No. 708,747, dated September 9, 1902, and in which each coupling head is provided with a laterally projecting hook-shaped portion adapted to engage the corresponding portion of a counterpart coupling by a relative lateral movement, and be rigidly locked together 40 by cam levers or latches, one pivoted upon each coupling head and bearing against the other counterpart coupling head. Train pipe passages are formed in the coupling heads and are provided with gaskets adapted 45 to abut against corresponding gaskets of the

counterpart coupling head when the two are connected together.

While a coupling of the above type will automatically couple with a counterpart coupling when two cars are brought together, it 55 is necessary to manually operate the train pipe valves to open the train pipe passages.

By the present invention, means are provided by which the train pipe valves are operated to open the train pipe passages when the cars are brought together for coupling up, the valve operating means being also adapted to be actuated, when the cars are being intentionally uncoupled, to close the open 60 ends of the train pipe sections, however the 65 construction is such that should the cars be unintentionally uncoupled the train pipe valves will not be actuated to close the train pipe passages.

Referring to the drawing, the automatic 70 train pipe coupling head 11 is provided with one or more train pipe sections 12, each having a passage adapted to register with the corresponding passage of a counterpart coupling, the joint between the adjoining ends 75 of the pipes being sealed by a gasket 13 mounted in the end of each pipe section.

Carried by the shank of the coupling head 11 and extending rearwardly therefrom is a 80 tubular section or sleeve 14 which is slidably mounted on a stem 15.

The rear end of the stem 15 is provided with a ball section 16 adapted to be mounted in a correspondingly formed socket (not shown) carried by the car.

A follower collar 17 is slidably mounted on the rear portion of the sleeve 14 and carries a pin 18 which extends through elongated slots 19 in the sleeve 14 and also through an elongated slot 20 in the stem 15.

A front follower collar 21 is also mounted on the sleeve 14 and carries a pin 22 which extends through elongated slots 23 in the sleeve 14 and also through an elongated slot 24 in the stem 15.

95 A coil spring 25 is interposed between the collars 17 and 21. This spring is adapted to be compressed upon movement of either collar relative to the other, and is also under initial compression, which tends to hold the 100

parts in the position shown in Fig. 1, with the pins 18 and 22 engaging the extreme ends of the corresponding guide slots.

At the front end, the stem 15 is provided with an extended portion 26 which is recessed to receive the end portion of a rack bar 27 and also the rear portion of a block 28.

The rack bar 27 is guided by a vertical rib 29 depending from the top wall of the coupling head 11, and this rack bar at its front end is provided with teeth which mesh with the teeth of a gear 30 carried by a plug valve 31 rotatably mounted in the train pipe section 12.

15 The plug valve 31 is adapted to close the train pipe passage 12 when the coupling is uncoupled and its port or waterway 32 is adapted to register with the train pipe passage when the coupling is connected to a 20 counterpart coupling to permit the fluid to flow through the connected train pipe sections.

The end of the rack bar 27 projecting into the portion 26 of the stem 15 is formed with 25 a laterally projecting arm 33 which is interposed between the end face 34 of the stem 15 and the end of the block 28.

The block 28 is provided with an elongated opening 35 into which extends one end 30 of a latch 36 pivotally mounted in the bottom of the rib 29 at 37. The opposite end of the latch is formed with an upturned nose 38 adapted to be disposed within a notch 39 formed in the bottom of the rack bar 27 for a purpose to be described.

40 The train pipe coupling is disposed below the usual car coupler 40 (see Fig. 4) and the block 28 is connected to the car coupler locking pin 41 by a flexible element, such for instance as a chain 42, so that when the locking pin 41 is lifted in the well known manner to release the car coupler, the block 28 will also be elevated for a purpose to be hereinafter described.

45 In operation, when cars are brought together for coupling up, the counterpart coupling heads engage and interlock in the usual manner. During this movement, the sleeve portion 14 is moved rearwardly and 50 carries with it the pin 22 and the follower collar 21. The rear follower collar 17 is held against rearward movement by engagement of the pin 18 with the stem 15, so that the spring 25 is compressed. In this manner the 55 coupling head 11 and the stem 14 will be telescoped together.

The extended portion 26 of the stem 15 is formed at its outer end with an inturned flange 43 and the block 28 is provided with a 60 step 44 which is adapted to be engaged by the flange 43 when the head 11 moves relatively to the stem 15, so as to prevent the block from traveling with the coupling head 1.

65 Furthermore, as the end 33 of the rack

bar 27 abuts the end face 34 of the stem, the rack bar will remain stationary when the coupling head 11 moves rearwardly on the stem 15, and as the gear 30 is carried by the coupling head, the plug valve 31 will be rotated to bring the port 32 thereof into registration with the train pipe passage 12, as will be readily understood.

The rearward movement of the coupling head 11 relative to the stem 15 will carry the 75 latch 36 inwardly of the opening 35 of the block 28, as well as position the nose 38 at the rear end of the notch 39 of the rack bar.

When cars are separated, the car couplers are first unlocked by lifting the locking pins 80 41 to permit uncoupling in the usual manner and as the cars separate, the train pipe couplings remain coupled until the cars have moved apart sufficiently to pull the coupling heads 11 outwardly of the stems 15 until 85 further longitudinal movement is prevented by the pins 22 engaging the outer ends of the slots 23, as shown in Fig. 1.

This action will also carry the latch 36 outwardly, but as the block 28 will be elevated 90 when the coupler locking pin 41 is lifted, the latch 36 will be tilted on its pivot 37 and its nose 38 will be disposed beneath the bottom of the rack bar 29.

When the block 28 is elevated as has been 95 described, the upper part of the portion thereof disposed with the portion 26 of the stem 15 will be disposed in substantially the same plane as the end 33 of the rack bar 27, and thereby the rack bar will be prevented from 100 moving outwardly with the coupling head 11. Therefore, when the coupling head 11 moves outwardly relative to the stem 15 when the cars are being uncoupled, the plug valve 31 will be rotated to close the train pipe passage 105 12.

For the purpose of effecting an emergency 110 rate of reduction of the fluid pressure in the train pipe 12 to cause immediate application of the brakes when the coupling heads are unintentionally uncoupled, the plug valve 31 should not be closed.

Therefore, should the coupling head 11 move outwardly on the stem 15 while the block 28 is resting on the bottom of the portion 26 of the stem 15 (see Figs. 3 and 4) the nose 38 of the latch 36 will be disposed in the notch 39 of the rack bar and the end 33 thereof will be disposed in a plane above the top of the block 28. When the coupling heads are pulled outwardly on the stems 15, the rack bars 27 will therefore be carried therewith, and hence will not cause the plug valves 31 to be rotated to a position closing the train pipe passage 12.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. A train pipe coupling comprising a fixed portion, a head removably mounted on said fixed portion, a train pipe passage in said movable head, a valve for controlling communication through said passage, an actuator for operating said valve, said actuator being mounted in said head and engageable with said fixed portion and also being removable relatively to said head, means for connecting and disconnecting said valve actuator to the head, and means for limiting the movement of the actuator relatively to said head when the actuator is disconnected therefrom.

2. The combination with a car coupler having movable locking means, and a train pipe coupling having a fixed portion and a head movably mounted thereon, a train pipe passage in said movable head, a rotatable valve for controlling the communication through said passage, a gear carried by said valve, a rack bar mounted in the head and in mesh with said gear, said rack bar being so mounted in the head as to be removable relative thereto, a notch formed in said rack bar, a latch pivoted to the head and adapted to engage in said notch to restrict the movement of the rack bar relative to the head, whereby said rack bar is caused to move in unison with the head and gear and thereby not rotate the gear, means formed on the rack bar for engaging the fixed portion of the train pipe coupling whereby said rack bar is held stationary when the coupling head is moved relatively to said fixed portion, and means connected to the movable car coupler locking means for operating said latch to disengage the same from said notch when the cars are uncoupled.

In testimony whereof I have hereunto set my hand, this 22nd day of November, 1928.

CLYDE C. FARMER.
